UNITED STATES PATENT OFFICE.

WINFRED L. COBB, OF JEFFERSON, OREGON.

AUTOMATIC DOOR FOR MAIL BOXES.

Application filed May 13, 1927. Serial No. 191,159.

This invention relates to receptacles especially designed for holding mail, an object being to provide a novel form of receptacle closure which will be normally closed, and 5 may be readily opened for the insertion or removal of mail matter.

Another object of the invention is the provision of means to facilitate the insertion of mail matter in the box when the latter is in 10 open position, so as to conserve the carrier's time, the means employed also providing a finger piece or grip for use in opening the receptacle.

With the above and other objects in view, 15 the invention further includes the following novel features and details of construction, to be hereinafter more fully described, illustrated in the accompanying drawings and pointed out in the appended claims.

20 In the drawings:—

Figure 1 is a fragmentary elevation of the invention showing the receptacle closed.

Figure 2 is a plan view of the same.

Figure 3 is an end view.

25 Figure 4 is an end view with the receptacle open.

Figure 5 is a sectional view through the receptacle showing the inner face of the closure with the latter in open position.

30 Figure 6 is a similar view with the receptacle closed.

Figure 7 is a fragmentary elevation at one end of the receptacle with the closure open and part of the receptacle broken away.

35 Figure 8 is a fragmentary end view showing the receptacle open and parts broken away.

Referring to the drawings in detail wherein like characters of reference denote corresponding parts, the reference character 10 indicates a receptacle which is shown as of circular cross section, although receptacles of other types may be employed. This receptacle is open at one end for the insertion and 45 removal of mail matter and may be supported by any suitable means, the receptacle being provided with a bracket 11 for attachment to a suitable standard or support.

The receptacle closure is in the form of a 50 plate or door 12 which has secured to one side of its center a strap 13. This strap extends above the upper edge of the door 12 and is bent upon itself as shown at 14 for engagement over the upper end of a post 15. The 55 post 15 extends upwardly from the receptacle 10 and the strap 13 is secured thereto by

means of a pivot pin 16. The door is thus hingedly secured to the receptacle for lateral swinging movement and is moved to closed position by its own weight. One edge of the 60 door is provided with a flange 17 which is shaped to fit the edge of the receptacle and provides a stop to limit movement of the door in the direction of closing.

The door is provided with an extension 18 65 which projects beyond the edge of the receptacle when the door is closed and this projecting portion is provided with a curved marginal flange 19 which extends at right angles to the face of the door. The flange is relatively wide and its curvature conforms to the curvature of the cross section of the receptacle 10. The flange 19 thus provides a finger piece or grip for use in swinging the door to an open position and when in an open position, this flange provides a guide to facilitate the insertion of newspapers and other mail matter into the receptacle. Opening movement of the door is limited by the engagement of the portion 14 of the strap 13 with a shoulder 20 provided on the post 15.

The invention is susceptible of various changes in its form, proportions and minor details of construction and the right is herein reserved to make such changes as properly fall within the scope of the appended claims.

Having described the invention what is claimed is:—

1. In combination with a receptacle having an opening, at one end a disk-like closure 90 for said receptacle, a flange at one marginal edge of the closure, means to hingedly support the disk-like closure for swinging movement across the opening to open and close the receptacle and to permit the flange to be 95 brought into position to provide a guide at the receptacle opening and a stop to locate the flange in guiding position when the receptacle is open.

2. In combination with a receptacle having an opening at one end, a disk-like closure for said opening, a flange at one marginal edge of the closure, means to hingedly support the disk-like closure for lateral swinging movement across the opening to open and close the receptacle and to permit the flange to be brought into position to provide a guide at the receptacle opening and a stop to locate the flange in guiding position when the receptacle is open.

3. In combination with a receptacle having an opening at one end, a disk-like closure

- for said opening, a flange extending outwardly at right angles from one marginal edge of the closure, means to hingedly support the disk-like closure for swinging movement across the opening to open and close the receptacle and to permit the flange to be brought into position to provide a guide at the receptacle opening and a stop to locate the flange in guiding position when the receptacle is open.
4. In combination with a receptacle having an opening, a closure for said opening, a post extending from the receptacle, a strap extending from one side of the center of the closure and pivotally secured to the post to provide a gravity operated hinge for said closure, a combined operating and guide

flange for the closure, means to limit closing movement of said closure and means to limit movement of the closure in an opposite direction. 20

5. In combination with a receptacle having an opening, a closure for said opening, a post extending from the receptacle, a strap extending from one side of the center of the closure and pivotally secured to the post to provide a gravity operated hinge for said closure, a combined operating and guide flange for the closure, means to limit closing movement of said closure and means included in the closure hinge to limit pivotal movement of said closure in an opposite direction. 25 30

In testimony whereof I affix my signature.
WINFRED L. COBB.
